UNITED STATES PATENT OFFICE

ERNEST A. FRANCE, OF BRIDGEPORT, AND HOMER G. KNODERER, OF FAIRFIELD, CONNECTICUT, ASSIGNORS TO GENERAL ELECTRIC COMPANY, A CORPORATION OF NEW YORK

FUSE BLOCK AND FUSE THEREFOR

Application filed September 11, 1929, Serial No. 391,879. Renewed May 25, 1932.

The invention relates to fuse devices adapted for use in a house wiring system. More particularly the invention relates to a type of device of the above character especially adapted to be inserted in a standard form of container located in the wall of a building provided with such a wiring system and adapted also to be made a part of standard equipment for such a system.

10 In order to increase the demand and reduce the cost of manufacture, distribution and installation of equipment for house wiring systems, it is essential to standardize the units of the system and to reduce to a minimum the number of such units and to so design such units that they may be installed or interchanged readily without the demand of high grade labor.

It is an object of our invention to contribute to the accomplishment of such results by providing an improved unit for such a system in the form of a fuse block and fuses thereon and an improved mounting therefor, such unit having a minimum number of 25 parts, being of simple design and adapted to be assembled and installed with a minimum of operations and labor and demanding a low maintenance cost.

The invention will be more readily understood from the following specification and claims, reference being had to the accompanying drawing, in which Fig. 1 shows the device of the invention in plan view; Fig. 2 shows the device of Fig. 1 in elevation; Fig. 3 shows the device as one of the elements in a house wiring system, together with the supporting means therefor, the elements being shown in so-called exploded view; Fig. 4 shows the frame for the fuse elements and 40 shows also all of the metal connections and terminals for the fuses and lines; Fig. 5 shows one of the fuse elements in elevation; Fig. 6 shows in perspective two of the metal terminals of the frame Fig. 4; Fig. 7 is a 45 diagrammatic layout of the circuit connection in and to the unit with the terminals on the block, and shows also the connections to the cables; and Fig. 8 is a modified form of the fuse of Fig. 5.

50 Referring more in detail to the drawing,

in Fig. 3 there is shown a lath and plaster wall with a hanger 2 secured to the stud 3. The hanger serves to support a box or receptacle 4, the body of which latter is adapted to be inserted in the compartment 5 of the hanger and secured to said hanger by any suitable means, as for example, by screws 6, which extend through the flange 7 and engage threaded holes 2' in the hanger. This receptacle is the subject matter of application Serial No. 391,900, filed in the names of Carlson and Knoderer, bearing the same filing date as this application. When in place, the flange 7 of the receptacle is seated on the rim 8 of the hanger or on the plaster 60 about said ring. The receptacle has a removable bottom element 10 to which a block 11 of insulating material may be secured, as for example, by means of screws 12. These screws are free to turn in the block in which they are held against longitudinal movement by pins 13, see Fig. 2. For convenience washers 13' are inserted between the block and the pins. As shown, the threaded portions of these screws are adapted to engage the 70 threaded holes 14 in the base element 10. This element is provided also with holes 15 arranged about the central axis of the base, which holes are adapted to receive each a cable 16. As shown in Fig. 3, two such cables 80 are represented. However, the number may be varied. In Fig. 7 five are indicated. Of these five conductors, one leads from the power line to the fuse block and the other four lead from the fuse block to the load 85 circuits. It may be assumed for the purpose of specification that each cable contains two conductors. One conductor in each cable may be connected to the base 10, for example, by means of screws 17 or by a number of such 90 screws, thus grounding one conductor in each cable to the base. This conductor may be bare. Each of the other conductors in the cable is connected to a terminal in the frame, Fig. 4. Each of these terminals corresponds 95 to a fuse, four such fuses, 19, 20, 21 and 22, being shown, see Fig. 1. In making the connections to the fuse block terminals the cables are first drawn in from behind the wall through the bottom opening 23 in the recep- 100

tacle 4, as indicated in Fig. 3, in order to simplify and expedite the work. After such connections are completed the block 11 is secured to the base 10 by the screws 12 and the base and fuse block are inserted in the box with the base seated on the rim at the bottom of the receptacle about the hole 23.

The top face 24 of the block 11 should be adjusted substantially flush with the top of the flange 7. This adjustment can be made by means of the screws 12, which may be turned to raise or lower the block 11 with respect to the base 10. This adjustment may be made before or after the elements 10 and 11 are inserted in the receptacle and in order that it may be made after, the holes 25' are provided in the cover ring 25 through which the screws 12 may be turned. When the block 11 is in place, the cover 25 is placed over the receptacle 4 and screwed to the flange 7 by means of the screws 26, thus clamping the base 10 securely in the bottom of the receptacle through the medium of the block 11. Inasmuch as the upper terminals or heads 54 of the fuses project above the surface 24, cover 25 is provided with holes 27, through which the heads of the fuses project and through which the fuses may be replaced.

With reference to the frame shown in Fig. 4, this frame may be slipped like a saddle over the block 11, as shown in Figs. 1, 2 and 3. The frame in the particular arrangement shown comprises a central metal piece 28 from the metal arms A, B, C, D of which 35 depend strips of insulation 29, 30, 31, 32. Arms A, B, C and D are electrically connected each, for example, by rivets 27 with the corresponding fuse terminal clips 33, 34, 35, 36. These rivets insure electrical connection 40 between these fuse clips and the corresponding arms of the central metal element 28, which latter is provided with a terminal 38, to which the wire connection, as for example, from the cable conductors may be secured by 45 means of a screw 39, as shown. The strips 29, 30, 31 and 32 are provided at their opposite ends with corresponding fuse terminal clips 40, 41, 42, 43, similar to clips 33, 34, 35, 36. The fuse clips 40 through 43 are in turn provided with terminal elements 44, 45, 46, 47, which are electrically connected with the corresponding fuse clips in the same manner as are the arms A through D with the clips 33 through 36. The terminals 44 through 47 are 55 provided with means whereby wires may be attached thereto, as for example, screws 48, 49, 50, 51. As shown, the fuses are inserted between the pairs of clips 33 and 40; 34 and 41; 35 and 42, and 36 and 43. The fuses are 60 preferably in the form of capsules, as shown in Fig. 5, having the usual metal bands 52 and 53, to which the ends of the fuse wire in the capsule are connected and which bands engage the fuse terminals of the fuse block. 65 On top, each capsule is provided with a ter-

73 minal head 54 of insulating material, by means of which the fuse may be withdrawn from the supporting clips or restored thereto through the holes 27 in the cover 25, Fig. 3. As indicated in Fig. 2, for example, when each fuse is inserted through the cover it is 75 pressed home until the bottom face 54' of the capsule strikes the transverse lower portion of the corresponding terminal. For example, this is indicated by the fuse 22, the lower surface of which is shown engaging the transverse lower portion of terminal 47, Fig. 2. By this arrangement, the proper location 75 of the capsule is insured.

In the form of device of Fig. 8 the head 54 is provided with a flange 55 to prevent the 80 fuse ever from falling into the receptacle and to prevent anyone from accidentally touching the metal portion 52 of the fuse.

Referring to Fig. 2, the block 11 is provided with grooves or depressions 57 which extends up underneath the screws 48, 49, 50, 51 and 39, for receiving the ends of the screws. As indicated in the drawing, all of the 90 terminals 48, 49, 50, 51 and 39 are conveniently located substantially along a transverse plane.

Referring to Fig. 1, it will be seen that the fuse carrying frame is secured to the block 11 by means of a screw 59 which passes 95 through central-frame element 28 and directly engages threads in the block 11. Preferably a threaded metal tube 60 into which the screw 59 threads is embedded in the block.

As previously indicated, one conductor in 10 each of the cables 16 may be connected to the base element 10 by means of the screw 17. One of these cables comes from the power 105 lines and the others run to load circuits of the system such as switches, convenience outlets, lamp brackets and the like through other receptacles such as receptacle 4. Each of the other conductors in the cables are secured by their respective screws 39, 48, 49, 50 and 51 to the terminals 38, 44, 45, 46 and 47, the other conductor of the cable leading from the power line being connected to terminal 38 and the other conductors of the cables leading to the load circuits being connected to terminals 44, 45, 46 and 47. With this arrangement the fuse clips 33, 34, 35 and 36 are connected in parallel to the power line, and the fuse clips 40, 41, 42 and 43 are connected to the respective load circuits.

With the arrangement shown each cable 11 leading off from the receptacle 4 toward other receptacles is provided with a fuse for the non-grounded conductor. The cable extending between the power lines and the fuse block is preferably not provided with a fuse in the 112 receptacle 4. In case of an overload in any one of the cables leading toward the other receptacles the corresponding fuse will blow and open up that branch of the circuit. If one of the fuses blows it can be quickly 112

and readily removed through its corresponding opening 27 in the cover 25, Fig. 2, and a new fuse substituted without the necessity of opening up the receptacle. Furthermore, in the event that a fuse block becomes defective in any way it may be readily removed as a unit and a new one substituted, or the metal frame Fig. 4 may be removed as a whole from the block and a new frame substituted. It will be seen, therefore, that the invention is a fuse device in a new and convenient form, very compact in arrangement and especially adapted to fit into a receptacle of standard size and design for a house wiring system and mounted so that it may be inserted or removed from the container as a unit, the unit being adjustable so that its longitudinal dimension may be adjusted to exactly fit the container. The new device is provided with improved means for holding the fuse capsules so that they may be readily inserted or removed from the clips, notwithstanding the fact that the unit is imprisoned in the receptacle by the cover thereof. The arrangement is such as to make it possible to readily re-fuse the device with no danger of any one coming in contact with the metal portions of the fuse device.

While we have elected to describe our invention with reference to a specific form of device such as illustrated in the drawing, we do not wish to be limited to such form, inasmuch as we contemplate variations and modifications within the spirit of the invention and the scope of the claims contained herein.

What we claim as new and desire to secure by Letters Patent of the United States, is:

1. A fuse support comprising a block of insulating material and a frame mounted thereon comprising a plurality of pairs of spaced fuse holding clips, the clips of each pair being insulated from each other, and terminals for connecting conductors to said clips.

2. A fuse support comprising a block of insulating material and a frame mounted thereon comprising a plurality of pairs of spaced fuse holding clips, the clips of each pair being insulated from each other and arranged along the sides of the block, and terminals for connecting conductors to said clips.

3. A fuse support comprising a block of insulating material and a frame mounted thereon comprising a central part which engages an end wall of the block and a plurality of pairs of spaced fuse holding clips carried by said central part and arranged along the side walls of the block, the clips of each pair being insulated from each other, and terminals for connecting conductors to said clips.

4. A fuse support comprising a block of insulating material, a plurality of pairs of fuse supporting clips arranged axially of the body in spaced relation to each other, the clips of each pair being insulated from each other, a terminal common to one clip of each

pair, and a separate terminal for the other clip of each pair.

5. A fuse support comprising a block of insulating material having recesses on opposite sides, pairs of fuse clips located in said recesses, the clips of each pair being insulated from each other, a central metal piece which embraces one end of the block and serves as a support for said pairs of clips, one clip of each pair being electrically connected thereto, a terminal on said central metal piece, and a separate terminal for the other clip of each pair.

6. In a wiring structure, the combination of a receptacle having an open end and a fuse support adapted to pass axially into the receptacle through said open end, said fuse support comprising a block of insulating material and pairs of spaced fuse supporting clips arranged axially of the block, the clips of each pair being insulated from each other and having their common axis parallel to the axis of the block whereby fuses supported by the clips present one end to the open end of the receptacle.

7. In a wiring structure, the combination of a receptacle having an open end, a fuse support adapted to pass axially into the receptacle through said open end, said fuse support comprising a block of insulating material and pairs of spaced fuse supporting clips arranged axially of the block, the clips of each pair being insulated from each other and having their common axis parallel to the axis of the block whereby fuses supported by the clips present one end to the open end of the receptacle, and a cover for the receptacle, said cover having openings through which fuses may be inserted into and withdrawn from the clips.

8. In a wiring structure, the combination of a receptacle having an open end, a base adapted to be inserted into the receptacle through said open end, said base having openings for the passage of cables, a block of insulating material attached to said base, and pairs of spaced fuse supporting clips carried by said block, said block and clips being adapted to be inserted into the receptacle through said open end.

9. A fuse supporting structure adapted to be inserted into a wiring receptacle comprising a block of insulating material and a frame carried thereby having a part which embraces one end of the block and pairs of fuse supporting clips carried thereby and spaced along the sides of the block, the clips of each pair being insulated from each other.

10. In a wiring structure, the combination of a receptacle having an open end, a base adapted to be inserted into the receptacle through said open end, said base having openings for the passage of cables, a block of insulating material, pairs of spaced fuse supporting clips carried by said block, said

block and clips being adapted to be inserted into the receptacle through said open end, and means for fastening said base and said block in the receptacle.

5 In witness whereof, we have hereunto set out hands this sixth day of September, 1929.

ERNEST A. FRANCE.
